Specification for Design.

Patented Apr. 25, 1911.

Application filed December 15, 1908. Serial No. 467,715. Term of patent 3½ years.

To all whom it may concern:

Be it known that I, ALBERT S. VAN DENBURGH, a citizen of the United States, residing at North Plainfield, in the county of Union and State of New Jersey, have invented a new, original, and ornamental Design for a Nose-Guard for Eyeglasses, of which the following is a specification, reference being had to the accompanying drawing, forming part thereof.

The figures of the said drawing clearly show my new, original and ornamental de-

sign; and in the drawings, Figure 1 is a perspective view, and Fig. 2 is a side view, showing my new, original and ornamental design.

I claim:—

The ornamental design for a nose-guard for eye-glasses, as shown.

ALBERT S. VAN DENBURGH.
